UNITED STATES PATENT OFFICE

STEPHAN LÖFFLER, DECEASED, LATE OF BERLIN-CHARLOTTENBURG, GERMANY, BY
JENNY ELFRIEDE LÖFFLER, SOLE HEIR, OF BERLIN-CHARLOTTENBURG, GERMANY

PROCESS FOR TREATING COALS, TARS, MINERAL OILS, AND THE LIKE, BY HYDRO-
GENATION UNDER HIGH PRESSURE AND AT HIGH TEMPERATURE

Application filed August 15, 1930, Serial No. 475,643, and in Germany November 27, 1926.

This invention relates to an improvement in the destructive hydrogenation of distillable carbonaceous materials, such as coals of all varieties and hydrocarbons such as tars or oils under high pressure and at high temperature.

Briefly stated, the invention consists in employing, before, during and after the reaction, high-pressure steam (superheated or saturated or condensed) for heating and cooling the participants in the reaction, such as coal, tar, oil, hydrogen, additions and the like. The term "participants in the reaction" where herein employed is also intended to include the reaction products. The pressure of said steam should be at least equal to that prevailing in the reaction chamber, or differ only slightly therefrom, for which purpose the reaction vessel is, for example, connected directly or indirectly with the heating and cooling chambers, a control member being interposed if desired.

Preferably the steam is led in closed circuits, the heating or cooling action being controlled in a simple manner by varying the volume in circulation, the temperature, or the like. The circulation may be positively maintained by means of pumps or the like. For the purpose of heat equalization in the several heating and cooling circulations, a common heat accumulator may be included, the heat content of which is modified, and into which surplus hot steam is admitted. The water level therein must be checked and regulated.

As a heat carrier in the pressure-hydrogenation of coal etc., steam offers a series of important and practical advantages over the gaseous media at present mainly employed for that purpose.

The apparatus needed for the gaseous heat carriers employed (namely, the plant for generating the respective gases, the high-duty compressor for compressing the gases to working pressure, the circulation pump which forces the heating gas in circulation through the heating apparatus and the heat-exchanging devices, and the apparatus for heating the heat carrier) is relatively extensive, complicated and therefore expensive to

install. The maintenance of a definite temperature and its regulation within the necessarily small margins of tolerance, is attainable only by arranging for the heat carrier to be heated by interposing an intermediate heat carrier (such as a lead bath or the like) in the heating apparatus, instead of direct. Moreover, owing to the high accumulation of heat (due to the physical properties of the gases concerned) in the walls of the pipes, the direct heating of the gaseous heat carriers, in coiled pipes or the like, would be dangerous. On the other hand, the interposition of the intermediate heat carrier introduces the drawback of rendering the control of the temperature tardy.

The steam employed as heat carrier in accordance with this invention, is generated in a high-pressure boiler which, at the same time, supplies the steam required for power purposes in the hydrogenation and attendant plants, and is easily and reliably controlled. The output required is less than when gaseous heat carriers are employed, the gas-producer plant and high-duty compressor for compressing the gas, being eliminated. Further, the maintenance of a definite temperature, with only very slight fluctuations, and the regulation of the temperature, or the alteration in the level of the temperature, is easily and reliably assured, in consequence of the direct heating of the steam in the superheater. Still further, the employment of steam results in more complete heat utilization of the heat carrier and reaction components, through the heat exchange between the two, the preheating of the feed water, the intermediate superheating and the like, and enables a satisfactory equalization of heat and temperature to be obtained in the various heating or cooling circulations, for example by the interposition of a joint heat accumulator, and by a storage of heat per se.

When steam is employed, the disk of corrosion is less than in the case of the usually employed heat carrier, hydrogen. Operating with steam is also far less dangerous than operating with hot hydrogen.

Various embodiments of plants for the treatment of coal and oil and the like are

illustrated, diagrammatically and by way of example, on the accompanying drawings.

In Fig. 1 reference 1 denotes the reaction vessel, into which coal or oil or the like is admitted, together with the requisite additions, at *a*, the hydrogen for hydrogenation being admitted at *b*, and the hydrocarbons being led away at *c* after the reaction has been completed. In many cases the reaction proceeds under heavy pressures (20-100 atmospheres and over) and high temperatures (300-500° C.). The reaction vessel 1 is enclosed in a pressure casing 2. High-pressure steam for heating, or for maintaining the reaction temperature, is admitted into the jacket space at *d*, said steam being supplied from a directly or indirectly heated boiler 3, with superheater 4, and distributed into the various pipes at *f*, by means of suitable control devices.

The steam issues from the jacket space at *e* and passes into a heat exchanger 5, in which the hydrogen required for the reaction is heated. The condensate from the hot steam is then returned to the boiler 3, for example by means of a pump P_1 .

The raw materials, additions, etc., are pre-heated by steam in a second heat exchanger 6, and the resulting condensate is also returned to the boiler 3 by means of the pump P_1 .

The boiler 3 also supplies steam to an engine 7, the condensate from which is likewise returned to the boiler 3.

The feed water for the boiler 3, for example the condensate from the engine plant 7, is forced by a pump P_2 into a heat exchanger 8, where it absorbs, in counterflow, the heat of the reaction gases, and is then conveyed to the boiler 3. The improved or treated oil and residues are drawn off from the heat exchanger 8 at *g*.

Fig. 2 represents another embodiment, with positive steam circulation in the several heating and cooling systems, the same reference characters being employed as in Fig. 1. The steam is generated in a high-pressure boiler 3 by superheated steam introduced from *f*, is led from the boiler at *h*, and is forced, in a positive manner by a pump P_3 or the like, through the fire-heated superheater 4 and into the consumption pipes at *f*.

A portion of the steam flows through the jacket space of the reaction vessel 1 and then into the heat exchanger 5, for heating the hydrogen. A second portion of the steam serves for preheating the raw materials, additions etc., in the heat exchanger 6. The steam condensate from 5 and 6 is led back into the boiler 3. A further portion of the steam serves for performing work in the engine plant 7. As in Fig. 1, the feed water is preheated, by the reaction gases, in the

heat exchanger 8, from which the gases are drawn off at *g* through a throttle 9.

The heating and cooling action can be regulated by varying the delivery of the pump P_3 , or by modifying the steam temperature, etc. Modification of the steam temperature can be effected by the heating of the superheater 4, or by mixing the steam with saturated steam in the various circulations, for example, from *i* out, through the pipes 10 and 11, by way of the control devices 12 and 13.

Fig. 3 represents a plant in which a joint heat accumulator 14, with water space and steam space, is connected up with the several heating and cooling circulations. In this case, the production and superheating of the steam for the various circulations are effected, for example, in separate, heated coils 15, 16 and 17, into which water is forced, at *k*, from the heat accumulator, by means of pumps P_4 , P_5 and P_6 . Surplus steam is returned to the heat accumulator by way of pipes 18, 19 and 20. Similarly, the feed water serving to cool the reaction products, and the condensate from the circulation of the reaction vessel and the preheating of the raw materials in 1, are led into the heat accumulator. The water level in said accumulator is checked by means of a water gauge 21, and is regulated by varying the rate of feed by the pump P_2 , or by drawing off water at *k*, by means of a throttle 22. The pressure in the heating and cooling systems is adjusted by the pressure in the reaction chamber, through the agency of a special control device 23, which is connected with the reaction chamber 1 and the steam space of the heat accumulator 14, by pipes 24 and 25. In this case, the heat exchangers 6 and 8 are designed as double pipe coils.

What is claimed is:—

1. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, passing the steam through a zone of still higher temperature, passing part of the steam thus heated into a zone surrounding the reaction zone and being in indirect heat exchange relationship therewith, thence passing said steam into indirect heat exchange relationship with the incoming hydrogenating gas, and thence returning the steam to the aforesaid confined space, passing another part of said steam into indirect heat exchange relationship with the incoming carbonaceous material and thence back to the said confined space, causing a further part of said high pressure steam to do mechanical work, passing the condensate thus produced into indirect heat exchange relationship with the

reaction products and then returning it to said confined space.

2. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, pumping the steam to a point of distribution, while simultaneously by means of the pumping regulating the amount of steam and its rate of flow, passing part of the steam through a zone of still higher temperature, bubbling part of the steam thus heated into the water contained in the said confined space, passing steam from the point of distribution together with steam coming from the said zone of higher temperature into indirect heat exchange relationship with the reaction zone, thence passing said steam into indirect heat exchange relationship with the incoming hydrogenating gas and thence returning the steam to the aforesaid confined space, passing another part of the steam from the point of distribution together with another part of the steam from the said zone of higher temperature into indirect heat exchange relationship with the incoming carbonaceous material and thence returning it to the confined space, passing water into heat exchange relationship with the reaction products, and then passing it into the said confined space.

3. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, passing the steam through a zone of still higher temperature, passing part of the steam thus heated into a zone surrounding the reaction zone and being in indirect heat exchange relationship therewith, thence passing said steam into indirect heat exchange relationship with the incoming hydrogenating gas, and thence returning the steam to the aforesaid confined space, passing another part of said steam into indirect heat exchange relationship with the incoming carbonaceous material and thence back to the said confined space and bringing the products of the reaction into indirect heat exchange relation with cooling water.

4. A process for the destructive hydrogenation of a distillable carbonaceous material, which comprises introducing a hydrogenating gas under a pressure of at least 20 atmospheres and a carbonaceous material into a reaction zone, withdrawing reaction products from the reaction zone, heating water in a confined space thereby producing high pressure steam, passing the steam through a zone of still higher temperature,

causing said steam to acquire a temperature of not less than 300° Celsius, passing part of the steam thus heated into a zone surrounding the reaction zone and being in indirect heat exchange relationship therewith, thence passing said steam into indirect heat exchange relationship with the incoming hydrogenating gas, and thence returning the steam to the aforesaid confined space, passing another part of said steam into indirect heat exchange relationship with the incoming carbonaceous material and thence back to the said confined space, causing a further part of said high pressure steam to do mechanical work, passing the condensate thus produced into indirect heat exchange relationship with the reaction products and then returning it to said confined space.

5. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, pumping the steam to a point of distribution, while simultaneously regulating the amount of steam and its rate of flow, passing part of the steam through a zone of still higher temperature, thereby causing said steam to acquire a temperature of not less than 300° Celsius, bubbling part of the steam thus heated into the water contained in the said confined space, passing steam from the point of distribution together with steam coming from the said zone of higher temperature into indirect heat exchange relationship with the reaction zone, thence passing said steam into indirect heat exchange relationship with the incoming hydrogenating gas and thence returning the steam to the aforesaid confined space, passing another part of the steam from the point of distribution together with another part of the steam from the said zone of higher temperature into indirect heat exchange relationship with the incoming carbonaceous material and thence returning it to the confined space, passing water into heat exchange relationship with the reaction products, and then passing it into the said confined space.

6. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, passing the steam through a zone of a still higher temperature, passing the steam thus heated into a zone surrounding the reaction zone and being in indirect heat exchange relationship therewith, maintaining the steam in said surrounding zone at substantially the pressure of said reaction zone,

thence passing said steam into indirect heat exchange relationship with the incoming hydrogenating gas, and passing another part of said steam into indirect heat exchange relationship with the incoming carbonaceous material.

7. A process for the destructive hydrogenation of a distillable carbonaceous material, which comprises introducing a hydrogenating gas under a pressure of at least 20 atmospheres and a carbonaceous material into a reaction zone, heating water in a confined space thereby producing high pressure steam, passing the steam through a zone of a still higher temperature, passing the steam thus heated into a zone surrounding the reaction zone and being in indirect heat exchange relationship therewith, maintaining the steam in said surrounding zone at substantially the pressure of said reaction zone, thence passing said steam into indirect heat exchange relationship with the incoming hydrogenating gas, and passing another part of said steam into indirect heat exchange relationship with the incoming carbonaceous material and thence back to said confined space.

8. In the destructive hydrogenation of a distillable carbonaceous material, treating the said material with a hydrogenating gas under a pressure of at least 20 atmospheres, maintaining a zone containing a participant in the reaction in indirect heat exchange relationship with a steam zone containing high pressure steam having a temperature approximating that which it is desired to give to said participant in the reaction, by having the one zone surrounding the other and maintaining the pressures in said zones substantially equal by varying the supply of steam to said steam zone in accordance with the pressure in said other zone.

In testimony whereof I affix my signature.

JENNY ELFRIEDE LÖFFLER,

Sole Heir of Stephan Löffler, Deceased.
